INVENTOR:

John C. Harrington.

UNITED STATES PATENT OFFICE.

JOHN C. HARRINGTON, OF PROVIDENCE, RHODE ISLAND.

BRACELET.

SPECIFICATION forming part of Letters Patent No. 292,016, dated February 5, 1884.

Application filed November 20, 1883. (No model.)

To all whom it may concern:

Be it known that I, JOHN C. HARRINGTON, of Providence, in the State of Rhode Island, have invented an Improvement in Bracelets, of which the following is a specification.

5 My invention relates to that class of bracelets the arms of which are made self-closing by means of a spring; and it consists in the improved construction of the joint for connecting the arms to the ornamental box, which serves to conceal the joint and spring, as hereinafter fully set forth.

10 Figure 1 is a side elevation of my improved bracelet. Fig. 2 is a top view of the same. Fig. 3 is a section showing the joint and spring when the arms are in their closed position, as in Fig. 1. Fig. 4 is a side elevation, showing the arms opened, with the side of the ornamental box removed, to show the position of 15 the joints and spring. Fig. 5 is an enlarged perspective view, showing the construction of the box and spring. Fig. 6 is a perspective view of one of the arms of the bracelet.

20 In the accompanying drawings, A A are the two arms of the bracelet, which may be made in forked form, as shown in Figs. 2 and 6, and also provided with a transverse groove, b, cut at the inner side of the forked arms A A, as shown in Fig. 6. The spring B, which serves 25 to close the arms A A, is preferably made in a U form, and is held in the box E, between the ends of the arms A A, as shown in Figs. 3 and 4. The box E, to which the arms A A are

35 jointed, is partly formed of the U-shaped piece C, the upright sides of which are provided with slots d, or equivalent perforations, adapted to receive the forked ends of the arm A. The U-formed piece D, provided with the notches e e, is adapted to pass within the sides of the piece C, the ends a a of the arm A entering 40 the notches e e, and serves to force the ends a a downward, so that the lower edge of the slot d will enter the transverse groove b. Thus, when the piece D is in position, the arms A A will be secured to the box, as shown in Figs. 3 and 4. 45

I do not of course limit my claim to the forked arms shown in the drawings, as my invention is equally adapted to the ordinary bracelet-arms of elongated cross-section, and a spiral spring may be employed instead of the 50 U-shaped spring shown in the drawings.

I claim as my invention—

1. In a bracelet, the combination of arms A A, provided with the transverse groove b, perforated piece C, holding-piece D, and spring B, 55 substantially as described.

2. The improved joint for bracelets, formed by a groove at the inner side of the bracelet-arm, the perforated piece adapted to enter the groove, and the holding-piece, all arranged 60 substantially as described.

JOHN C. HARRINGTON.
